FIG. 5.

UNITED STATES PATENT OFFICE.

JOHN WALDHEIM, OF NEWARK, NEW JERSEY, ASSIGNOR, BY MESNE ASSIGNMENTS, TO UNION TYPEWRITER COMPANY, OF JERSEY CITY, NEW JERSEY, A CORPORATION OF NEW JERSEY.

TYPE-WRITING MACHINE.

1,021,393.

Specification of Letters Patent. Patented Mar. 26, 1912.

Application filed December 5, 1911. Serial No. 663,984.

To all whom it may concern:

Be it known that I, JOHN WALDHEIM, citizen of the United States, and resident of Newark, in the county of Essex and State 5 of New Jersey, have invented certain new and useful Improvements in Type-Writing Machines, of which the following is a specification.

My invention relates to typewriting machines and more particularly to tabulating mechanism.

The main objects of my invention, generally stated, are to provide comparatively simple and efficient tabulating mechanism 15 by which any desired columnar position may be selected at will, and by which any desired denominational position in a column may be selected, so that the carriage may, after a single run, be arrested at any desired columnar field or at any desired denominational position within any selected columnar field.

A further object of my invention, generally stated, is to provide comparatively 25 simple and efficient means whereby certain parts of the tabulating mechanism may be locked in the position to which the said part or parts may be set or moved under key control, and to automatically release 30 the locking means during a subsequent operation of the tabulating mechanism.

A still further object of my invention is to provide tabulating mechanism for arresting the carriage at variable positions in 35 the travel thereof, the variable position of arrest of the carriage depending on a variable movement of a fulcrumed member, and a variation of the fulcrum of said member bringing about a variation in the movement 40 which may be given to said member.

To the above and other ends which will hereinafter appear, my invention consists in the features of construction, arrangements of parts and combinations of devices 45 to be set forth in the following specification and particularly pointed out in the appended claims.

In the accompanying drawings wherein 50 like reference characters indicate corresponding parts in the various views, Figure 1 is a fragmentary, vertical, fore and aft sectional view of a typewriting machine showing an embodiment of one form of construction made in accordance with my invention, the section being taken on the line

w—w of Fig. 3 and looking in the direction of the arrows at said line. Fig. 2 is a detail perspective view of a group of two of the key actuated levers, together with certain of the associated parts for actuating the denominational stops. Fig. 3 is a fragmentary horizontal sectional view of the machine, the section being taken on the line x—x of Fig. 1 and looking in the direction of the arrows at said line. Fig. 4 is a fragmentary detail sectional view of the denominational stop levers and certain of the associated parts, the section being taken on the line y—y of Fig. 1 and looking in the direction of the arrow at said line. Fig. 5 is a diagrammatic side elevation, partly in section, of the tabulating mechanism, the view illustrating the parts in the actuated positions with the column selecting and denominational keys depressed. Fig. 6 is a like view of a part of the same with the parts disposed in the positions which they assume when the column selecting key is depressed.

In the accompanying drawings I have 80 shown only so much of a typewriting machine as may be necessary to arrive at an understanding of my invention.

I have shown my invention embodied in the present instance in a No. 15 Yost machine, except in so far as the tabulating mechanism of that machine may be modified or replaced by features of the present invention and except in so far as that machine may be modified to effect an embodiment of my present invention therein. Moreover, some of the parts of the typewriting machine are conventionally represented in order to simplify the showing. It should be understood, however, that the invention may be embodied in various styles 85 of typewriting machines and that various changes may be made in the construction to facilitate such embodiment.

The present case is one of three companion applications filed by me of even date here-with, the other applications bearing Serial Nos. 663,982 and 663,983 respectively. Considered from certain broader aspects there are features in common in all three cases. 105 The broader claims to features common to all three applications are included in case Serial No. 663,982, whereas any feature common alone to case Serial No. 663,983 and the present application are broadly 110

claimed in case Serial No. 663,983, the claims herein being restricted to features not disclosed in either of the other companion applications.

5 The frame of the machine comprises side plates 1 united by a rear cross plate 2 and top plates 3 and 4. A carriage 5 is mounted to travel from side to side of the machine on anti-friction balls or rollers 6; a cylindrical platen 7 being carried by the carriage. The carriage is moved in the letter feed direction under the power applied thereto by the usual spring drum 8. The usual or any suitable escapement mechanism is employed to 10 control the carriage in its step-by-step letter feed movement, only so much of the escapement mechanism being shown as may be of value in the consideration of the present invention. Thus a horizontally disposed feed 15 rack 9 is provided with upwardly extending arms 10 pivoted at 11 to depending lugs 12 on the bottom of the carriage. A spring 13 tends to force the feed rack forwardly into engagement with a feed pinion 14 which is 20 operatively connected to the usual escapement devices. A cross bar 15 is fixedly connected to the frame of the machine, and constitutes a support for a bracket 16, fixed to the cross bar by screws 17. A releasing device 25 or lever 18 is pivoted on a shouldered pivot screw 19, carried by the bracket 16. An engaging face or shoe 20 is provided on the release lever for contact with the feed rack 9, to effect a rearward movement thereof 30 of against the pressure of the spring 13 to disengage the feed rack from the pinion and thus free the carriage from control of the escapement mechanism. The carriage release device 18 is actuated in a manner which 35 will hereinafter appear.

40 A column stop bar 21 extends substantially throughout the length of the carriage and is supported thereby on arms 22 which project from the carriage. The column stop bar is provided with teeth 23 on opposite sides thereof for the reception of bifurcated sheet metal column stops 24 in the interdental spaces between the teeth on the bar. It will be understood that adjacent inter- 45 dental spaces are situated a letter space distance apart and that the column stops may therefore be adjusted to different letter space positions along the column stop bar throughout the length thereof. From an inspection 50 of Fig. 1 it will be understood that the column stops 24 have contact portions which extend rearwardly from the column stop bar at varying distances, so as to provide a series of graduated column stops, each having 55 a contact portion in a path of travel different from the others. The longest column stop 24 is situated at the right and the shortest at the left of the series on the column stop bar. In the present instance four column 60 stops are shown.

A series of denominational stops 25 is arranged for movement fore and aft of the machine in openings in a guide plate 26 fixed to the top plate 4 of the machine. This guide plate is provided with slots or openings 27, as shown in Fig. 4, to support the denominational stops against lateral movement and to guide said stops in their movements fore and aft of the machine. In the present instance each denominational stop 25 constitutes a part of a variably movable actuating lever or fulcrumed member 28, the levers extending upwardly in the rear part of the machine and being connected to key controlled actuating devices in a manner 75 which will hereinafter appear. Each of the fulcrumed members or levers 28 has a segmental slot 29 which extends longitudinally thereof intermediate the ends of the lever. When the members 28 are in the normal position all of the segmental slots 29 are in register and a single fulcrum or pivot rod 30 extends through the slots 29. From an examination of Fig. 4 it will be observed 80 that spacing sleeves 31 surround the fulcrum rod 30 and are arranged intermediate the levers 28 in order to maintain them properly spaced apart on their pivot rod. The ends of the fulcrum rod 30 are secured by screws 32 to supporting arms 33, arranged outside of the series of levers 28 and extending fore and aft of the machine. These supporting arms 33 are pivotally supported at their forward ends on a shaft 34, which latter is fixed by screws 35 in bearings in upwardly extending bracket arms 36. The arms 36 are, or may be, formed as a part of a cross bar 37 fixed to the frame 85 of the machine. From an inspection of Figs. 1 and 3 it will be observed that a universal 90 bar 38 has its bent ends riveted at 39 to the side supporting arms 33 which support the fulcrum rod 30. The universal bar 38, side arms 33 and the fulcrum rod 30 thus constitute a frame adapted to swing around the 95 shaft 34 as a center. This frame is connected to one end of a contractile spring 33^a, the other end of said spring being connected to one of the bracket arms 36 so as to exert a pull on the frame to return it to the normal 100 position, shown in Fig. 1. The under side of the universal bar 38 is provided with a series of stepped contact faces 40, so as to afford a differential swinging movement of the fulcrum carrying frame 38-33 under 105 the control of column selecting keys, as will hereinafter appear. From an inspection of Fig. 1 it will be seen that each slot 29 is in an arc of which the shaft 34 is the center. It will be understood therefore that a swinging 110 movement of the frame which carries the pivot rod 30, is adapted to move said pivot rod or fulcrum longitudinally of the slots 29 to any of the positions indicated, for 115 example, at *a*, *b*, *c* and *d* in Fig. 1, without 120 125 130

disturbing the levers 28 from their normal positions. Obviously, however, each of the levers 28 is adapted to receive a variable movement, depending on the position of the 5 fulcrum rod 30 in the slots 29.

The key actuated means by which a variable position of the fulcrum rod 30 is attained, in the present instance, comprises a series of four so-called, column selecting 10 keys 41, arranged in rear of and above the denominational keys 42, and in the rear of the ordinary printing keys in the keyboard of the machine. Each column selecting key is provided with a stem 43 slotted to receive 15 the forward end of a key actuated lever 44, pivoted on a pivot rod 45, fixed to the frame of the machine. From an inspection of Fig. 3 it will be observed that collars 46 are secured by screws 47 to the pivot rod 45 outside 20 of the right-hand and left-hand key levers 44. Intermediate spacing sleeves 48 are mounted on the pivot rod 45 between the levers 44 to maintain them properly spaced and to prevent the movement of the levers 25 along the pivot rod 45. Each of the levers 44 is, as will be seen, pivoted intermediate of its end so as to constitute a lever of the first order, the rear end of each of the first three of said levers, counting from right to 30 left, having an interiorly threaded bearing portion 49 for the reception of a screw 50. Each screw constitutes an adjustable contact device for coöperation with one of the contact faces 40 on the universal bar 38. The 35 levers 44 are of uniform length and have an equal extent of key depression which is limited by a contact face 51 on each lever engaging the shaft 34, as shown in Fig. 6, thereby arresting the fulcrum carrying 40 frame and fulcrum rod 30 in their movements to the shifted positions. The stepped faces 40 on the universal bar 38, however, afford varying extents of movement by different column selecting keys 41, through a 45 differential or variable movement of the frame and the fulcrum rod 30 which is carried thereby, as has been hereinbefore explained. Each key stem 43 of the column selecting keys, is guided in openings in guide 50 plates 52 and 53. A coiled expansion spring 54 surrounds each key stem, and bears at its lower end against the guide plate 53 and at its upper end against the associated lever 44 to elevate the key and return the parts connected therewith to normal position. Each key stem is limited in its upward movement by an enlargement 43a at the lower end thereof engaging the guide plate 53. 55 Referring now to the mechanism by which the denominational stops are actuated, it will be seen that the denominational keys 42, which in the present instance are ten in number, each has a key stem 55 like the 60 key stem 43, and received and guided in

openings in the guide plates 52 and 53. Each key stem 55 is slotted to receive the forwardly projecting arm of an angular lever, indicated as a whole by the reference numeral 56. From an inspection of Fig. 2 70 it will be seen that each of these levers comprises a forwardly extending arm 57, carried by a yoke-like member 58, which extends transversely of the machine and has rearwardly extending arms 59 which are 75 pivoted on a pivot rod 60, said rod being secured at its ends to the frame of the machine. These yoke-like members 58 are nested as shown, and are maintained spaced apart by washers 61, whereas collars 62 are 80 fixed to the pivot rod 60 by screws 63, to maintain the nested levers from moving longitudinally along the pivot rod. Each of the yoke-like levers or actuating members has one of its arms 59 arranged near 85 the center of the machine so that said inner arms may be utilized to transmit movement to certain actuating devices located centrally of the machine, notwithstanding the width of the series of denominational keys which 90 are connected to the yoke-like portions of the key levers. From an inspection of Figs. 1 and 2 it will be seen that adjacent to each of the inner arms 59 of the denominational key levers there is arranged an actuating 95 lever or member 64, provided with an offset laterally extending projection or lug 65 which extends beneath the inner arm 59 of the adjacent denominational key lever. These levers 64 are pivoted on the pivot rod 100 60 and each has a depending arm which is connected at 66 to a rearwardly extending push link 67. Each link, at its rear end, extends through a guide opening in a guide plate 68, fixed to the frame of the machine. The rear end of each link 67 is pivoted at 69 to the lower end of an associated denominational stop lever 28 and by which the lever is supported and actuated. A contractile spring 70 is connected at one end to the 105 depending arm of a lever 64 and at its forward end to a plate 71 secured to the frame of the machine. Each lever 64 has an upwardly extending arm 72 for purposes which will hereinafter appear. It will be 110 understood that the returning spring 70 for each lever 64 is effective to return the associated key actuated denominational lever 56 and its denominational key 42 to normal position. The pull exerted by the spring is 115 likewise effective to move the link 67 forwardly and return the associated denominational stop lever 28 to its normal position around the fulcrum rod 30. The forward movement of the lower end of each stop lever 28 is limited by contact with the guide plate 68, whereas a rearward movement of the lower end of each stop lever is limited by a set screw 73, received in a tapped opening 120 in the frame of the machine. 125 130

At the depression of a denominational key, movement is transmitted through the associated denominational lever 56. The movement of the latter around the pivot 60 5 is effective to move the associate lever 64 against the pull of the spring 70, and to actuate the corresponding denominational stop lever 28. A turning movement of the latter around its pivot 30 is effective to 10 move the corresponding denominational stop into the path of one or another of the column stops, depending on the extent of movement of the lever 28, and its extent of movement is dependent, as hereinbefore explained, upon the position of the pivot rod 15 or fulcrum 30 for the levers 28. The four positions of the pivot rod 30 to vary the extent of pivotal movement of each of the levers 28 are shown at *a*, *b*, *c* and *d* in Fig. 1. It will be understood therefore that an actuation of a column selecting key 41 is first 20 effected, in order to determine the position of the fulcrum rod 30, and to determine with which of the column stops the denominational stops are to coöperate; in short, to 25 select the column or columnar field where the carriage is to be arrested by the co-operation of the different denominational stops therewith. Thus, should the operator 30 desire to arrest the carriage in the second columnar field, it is merely necessary to depress the second column selecting key from the left, bearing the index numeral "2". The effect of the depression of this key is to 35 bring the contact device 50 carried thereby into engagement with the corresponding contact face or step 40 on the differential universal bar 38 and to swing the frame, of which the said bar is a part, around the 40 shaft 34 as a center. The depression of this column selecting key is effective to move the frame when the pivot rod 30 will be positioned, as indicated at *b* in Fig. 1. If, therefore, any denominational key be 45 depressed while the fulcrum rod 30 is in this position, then the corresponding denominational stop will be projected into the path of the second of the column stops 24, counting from left to right, to arrest the carriage 50 within the second columnar field and at a denominational position within said field corresponding to the particular denominational key depressed. It will be understood that each denominational stop will at this 55 time be moved a uniform distance and will be brought into the path of this same second column stop, as hereinbefore indicated.

I have found it desirable to provide locking means for locking the fulcrum rod 30 in 60 any one of the three positions indicated at *b*, *c* and *d* in Fig. 1 to which the fulcrum rod may be shifted, in order that the operator after depressing a column selecting key may release it and be free to actuate the denominational stop at will and without the 65

necessity of maintaining pressure on the column selecting key until after the denominational key is actuated. To this end I have provided each key lever 44 with an upwardly extending engaging member 74 having inclined edges or cams 75 and 76 on the front and rear sides thereof, respectively. The lower edge of each inclined edge terminates at a locking notch or slot 77. A universal locking device or bar 78 is carried by arms 79 arranged on opposite sides of the series of levers 44. These arms are pivoted on the pivot rod 60 and are held against movement longitudinally thereof by collars 79^a. The locking bar is therefore adapted to swing 80 around said pivot rod 60 as a center fore and aft of the machine. This locking bar is adapted to coöperate with the inclined edges 75 and the forward locking notches 77 of the engaging devices. A second locking bar 85 is connected in a like manner to arms 81 which are pivoted on the pivot rod or shaft 60. This locking bar 80 is adapted to coöperate with the inclined edges 76 and the rear set of locking notches 77. A contractile spring 82 is connected at one end to a pin 83 which extends upwardly from the locking bar 78, whereas the opposite end of said spring is connected to a pin 84 which extends upwardly from the locking bar 80. 90 The spring therefore exerts a pull to cause the locking bar 78 to be held against the inclined faces 75 on the members 74. It also tends to cause the two bars 78 and 80 to be drawn toward each other, but the bars under certain conditions which will herein-after appear are limited in their movements toward each other by a projecting arm 85 which extends forwardly from one of the arms 81 for engagement with an arm 79 of the forward locking bar, as shown in Fig. 1. The relative movement of the bars 78 and 80 toward each other is thus limited. A contractile spring 86 is connected at one end to the pin 84 and at its opposite end to the 95 shaft 34. The pull of this spring is greater than the pull of the spring 82, and the spring 86 tends to normally maintain the parts in the position shown in Fig. 1. If at this time a column selecting key be depressed, as indicated in Fig. 6, the rear end of the corresponding key lever will be elevated. The inclined edge or cam 75 will effect a forward movement of the locking bar 78 to move it against the pull of its 100 spring 82 until the forward locking notch 77 has been brought into register with the forward locking bar. The spring 82 is then effective to move the locking bar 78 into the notch, to lock the rear end of the actuated lever 44 in its elevated position, thereby locking the associated contact device 50 in its shifted position and maintaining the fulcrum 30 up in the position to which it has 105 been shifted on the depression of the col- 110

115

120

125

130

umn selecting key. The parts will remain in this position until a denominational key is depressed to effect a forward movement of the denominational stop. When this is done 5 the movement of the lever 56 is effective to produce a movement of the corresponding lever 64, thereby moving the upper arm 72 of this last mentioned lever forwardly to effect a forward movement of the locking 10 bar 80 into the rear locking notch 77, as represented in Fig. 5. As the locking bar 80 moves forwardly the contact arm 85 is effective to force the locking bar 78 to the releasing position as shown in Fig. 5, there- 15 by disengaging it from the locking projection 74. There is a slight drop between each engaging device 74 and the locking bar 80 to assure proper engagement between these parts when a disengagement is effected be- 20 tween a locking device and the locking bar 78. It will be seen that while the locking bar 78 is disengaged from the key actuated lever 44 it, nevertheless, is at this time main- 25 tained locked against return movement by the locking bar 80. When, however, the carriage has completed its travel and been arrested by a coöperation of the previously selected column stop with the denomina- 30 tional stop 25 controlled by the particular key depressed by the operator, then the denominational key may be released and as it returns to normal position the associated arm 72 will move rearwardly. This move- 35 ment of the arm 72 releases the locking bar 80, and the returning spring 86 moves the said locking bar out of the rear notch 77 and out of engagement with the locking projec- 40 tion 74 on the previously depressed column selecting key 44. This key lever 44 may therefore return to normal position as shown in Fig. 1, where it is again in position to be actuated by the depression of the appropriate column selecting key and to be automatically locked in its actuated position. 45 During the return of the locking bar 78 to normal position it is prevented from reengaging in the forward notch 77 of the actuated lever 44 by reason of the drop which has been effected between the engag- 50 ing member 74 on the actuated lever and the locking bar 80, as previously described. From the foregoing it will be seen that at the depression of a column selecting key to move the fulcrum 30 to the appropriate position determined by the particular column selecting key actuated, the parts will be automatically locked in the actuated position. That is to say, the column selecting key will be locked in the depressed position, the contact device 50 will be locked in its actuated position up against the universal bar 38, and the frame carrying the fulcrum rod 30 will be locked against return movement under the pull of the spring 33^a and in the position to which it has been moved by 55

depression of the column selecting key. It will also be understood that upon the first depression of a denominational key the locking mechanism will be automatically released to afford a return movement of the parts to normal position. 70

I have provided means whereby the release of the carriage to effect a tabulating operation or movement does not take place until the column selecting key has been depressed and locked in its operative position, and until a denominational key has been depressed. In order to provide against the release of the carriage until after a column selecting key has been depressed, I have provided means whereby the carriage release mechanism is normally inoperative and cannot be released unless a column selecting key has been actuated prior to the actuation of a column selecting key. Thus each of the levers 64 is provided with a rearwardly extending engaging projection 87, which, in the normal position of the parts shown in Fig. 1, is arranged above a universal releasing bar or device 88 carried by depending arms 89, pivoted to turn on a rock shaft 90, so that the universal releasing bar is mounted to swing fore and aft of the machine. The rock shaft 90 carries a rearwardly extending crank arm 91 provided at its rear end with a stop 92 which engages a cross bar 93 of a frame 94. The rear end of the crank arm 91 has pivoted thereto at 95 an upwardly extending link 96 which in turn is pivoted at 97 to the inner ends of two toggle links 98. The rear end of the rear toggle link is pivoted at 99 to a bracket 100, secured to the cross bar 15, whereas the forward end of the forward toggle link is pivoted at 101 to the carriage releasing device 18. 100 It will be understood therefore that a rearward movement of the universal releasing bar 88 is effective to turn the crank arm 91 upwardly, thereby transmitting movement through the links 96 and 98 to the carriage releasing device 18, which movement is effective to shift the feed rack 9 rearwardly out of engagement with the coöoperative feed pinion 14. As hereinbefore stated, the normal position of the parts is such, however, that the actuating projections 87 will not engage the releasing bar 88, so that a depression of a denominational key, when the parts are in the positions represented in Fig. 1, would be ineffective to produce a tabulating movement of the carriage, inasmuch as the carriage release mechanism could not be actuated. I have provided means, however, controlled by a depression of a column selecting key for elevating the 115 universal bar 88 into the path of the engaging projections or contact devices 87, in order to afford an actuation of the carriage release mechanism after a column selecting key has been depressed. Thus the frame 94, 120 125 130

hereinbefore referred to, comprises parallel side arms which are pivoted at 102 to rearwardly extending arms 103 on the bracket 36. The frame therefore is mounted to turn 5 on the pivots 102 as a center, in order that the forward end of the frame may be elevated from the position shown in Fig. 1 to that indicated in Fig. 5, where the releasing bar is held in coöperative relation with the 10 engaging projections 87, on the levers 64. The means for swinging the frame in the manner specified consists, in the present instance, of hook-like extensions 104 on the key levers 44. One of these depending hook-like 15 engaging projections is provided on each lever 44, and they normally extend beneath the pivot rod 90. An upward movement of the rear end of any of the levers 44 is effective to bring about an engagement 20 between the engaging hook 104 on the lever and the pivot rod 90 to swing the frame 94 around its pivots 102, from the position shown in Fig. 1 to that indicated in Fig. 5. At this time, therefore, the releasing bar 25 and the carriage release mechanism controlled thereby are adapted to be actuated, to release the carriage from the control of the escapement mechanism to afford a free travel of the carriage until it is arrested by 30 the coöperation of a column stop with the projected denominational stop. A contractile spring 105 is connected at one end to a pin 106 projecting from the crank arm 91. The opposite end of this spring is connected 35 to a pin 107 which extends from the fixed cross bar 37. The power of this spring is exerted to pull the arm 91 down, thereby moving the releasing bar 88 forwardly to normal position. This also effects a down 40 pull on the link 96 to tend to maintain the releasing device 18 in the position shown in Fig. 1. The stop 92 engages the cross bar 93, thus limiting the downward movement of the rear end of the crank arm 91 and the 45 parts controlled thereby. The power of the spring 105, connected in the manner described, is likewise effective to move the frame 94 downwardly at its forward end and maintain the universal bar out of coöperative 50 relation with the projections 87. The spring 105 therefore acts for a two-fold purpose. Stops 108 are carried by the side arms of the frame 94 and contact with the cross bar 37 to limit the downward swinging movement of the frame 94 under the 55 pull of its returning spring 105.

From the foregoing description it will be understood that in order to effect a tabulating movement of the carriage it is necessary 60 to first actuate an auxiliary or column selecting key in order to render the key controlled carriage releasing mechanism operative; that such depression of a column selecting key is effective to determine the position 65 of the fulcrum 30 for the denomina-

tional stop levers 28; that when the fulcrum is shifted it is automatically locked in its shifted position by the engagement of the locking bar 78 with a projection 74 on the actuated column selecting lever 44; that a 70 denominational key may now be depressed and its depression is effective to give the requisite amount of throw of the corresponding denominational stop lever, to bring the corresponding denominational stop into the 75 path of the particular column stop which has been selected, as determined by the operation of the particular column selecting key actuated; that at or about the time the denominational stop has been given the 80 requisite amount of movement to interpose it in the path of the proper column stop, a release of the carriage will be effected to afford a movement of the carriage until such time as the projected denominational 85 stop and the selected column stop are brought into coöperation to arrest the carriage; that when pressure is released on the denominational key, the locking mechanism 90 will be automatically released to afford a return movement to normal position of the column selecting key and the parts controlled thereby. It will also be understood that the variation in the position of the fulcrum rod 30 brings about and determines 95 the variation in the extent of movement that may be transmitted to each of the denominational stops; that the means by which the fulcrum rod 30 is shifted relatively to the denominational levers 28 constitutes leverage changing means by which the extent of movement of each denominational stop is controlled and the columnar position of arrest of the carriage is determined, and that the variable movements of 100 the denominational stops are toward and away from the column stops or in the direction in which the denominational stops move to bring them into coöperative relation with 105 the column stops.

It should be understood that when the parts are in the normal position the fulcrum rod 30 is maintained in the lowermost position, as indicated in full lines in Fig. 1, and that this position is one of the four which determines the extent of movement to be transmitted to the denominational stop levers. In other words, when the fulcrum 30 is in the position indicated at *a* in Fig. 1, the denominational stop levers will receive their greatest extent of throw in order to enable the denominational stops to be interposed in the path of the shortest column stops, or the first of the column stops, counting from left to right, and it is unnecessary to shift the fulcrum from this position. The left-hand column selecting lever bearing the index numeral "1", therefore terminates before it reaches the universal bar 38, and has no contact device 50 like the other three col- 110

115

120

130

umn selecting key levers. It follows that when this first column selecting key lever is depressed, no movement will be transmitted to the fulcrum carrying frame, and the fulcrum will remain in the position indicated at "a" in Fig. 1. Inasmuch, however, as the carriage release mechanism cannot be actuated until after the depression of a column selecting key I have provided a column selecting key bearing the index numeral "1" in order that this key may be actuated to carry the releasing bar 88 up into position where it may be actuated by the engaging projections 87. In other words, while it is unnecessary to actuate the first of the column selecting keys in order to determine the position of the fulcrum 30, it is necessary to actuate said key in order to render the denominational stop mechanism operative to release the carriage.

From a consideration of the foregoing description it will be seen that if the operator desires to use the construction as a mere column selecting mechanism, it is only necessary to depress the column selecting key and then depress the denominational key bearing the index mark indicating the decimal point. The carriage will be released on the depression of this last mentioned key and will be arrested after a single travel at the desired columnar field. If, however, it is desired to select a given denominational position, say, at ten thousands position within, say, the second columnar field, the column selecting key bearing the index numeral "2" is first depressed and the ten thousands denominational key is then depressed, and the carriage will after a single run be arrested in the ten thousands position in the second columnar field.

I believe that I am the first to devise the combination of coöperative tabulator stops and leverage changing means operable at will to cause a variation in the extent of movement of certain of said stops relatively to others to vary the point of arrest of the carriage, and wish to be understood as claiming such subject-matter broadly.

Various changes may be made without departing from the spirit and scope of my invention.

What I claim as new and desire to secure by Letters Patent, is:—

1. In a typewriting machine, the combination of a carriage; and tabulator mechanism for arresting the carriage at variable positions in the travel thereof, said mechanism including a fulcrumed member movable varying extents and by the variation in extent of movement of which a variation in position of arrest of the carriage is determined, and means for varying the position of the fulcrum of said member and thereby cause a variation in the extent of movement which may be given said member.

2. In a typewriting machine, the combination of a carriage; and tabulator mechanism for arresting the carriage at variable positions in the travel thereof, said mechanism including a fulcrumed member movable varying extents and by the variation in extent of movement of which a variation in position of arrest of the carriage is determined, and a series of keys for varying the position of the fulcrum of said member and thereby causing a variation in the extent of movement which may be given said member, each of said keys controlling a different position of the fulcrum.

3. In a typewriting machine, the combination of a carriage; and tabulator mechanism for arresting the carriage at variable positions in the travel thereof, said mechanism including a fulcrumed member movable variable extents and by the variation in the extent of movement of which the variation in position of arrest of the carriage is determined, means for varying the position of the fulcrum of said member and thereby causing a variation in the extent of movement which may be given said member, and means for locking the fulcrum in any of the variable positions to which it may be moved.

4. In a typewriting machine, the combination of a carriage; and tabulator mechanism for arresting the carriage at variable positions in the travel thereof, said mechanism including a fulcrumed member movable varying extents and by the variation in extent of movement of which the variation in position of arrest of the carriage is determined, key controlled means for varying the position of the fulcrum of said member to change its leverage and thereby cause a variation in the extent of movement which may be given said member, and automatically operating means for locking said fulcrum in any of the variable positions to which it may be moved.

5. In a typewriting machine, the combination of a carriage; and tabulator mechanism for arresting the carriage at variable positions in the travel thereof, said mechanism including a variably movable fulcrumed member, by the variable movement of which the variation in position of arrest of the carriage is determined, key controlled means for varying the position of the fulcrum of said member and thereby causing a variation in the movement which may be given said member, automatically operating means for locking said fulcrum in any of the variable positions to which it may be moved, and automatically operating means for releasing said fulcrum to enable it to be restored to normal position.

6. In a typewriting machine, the combination of a carriage; and tabulator mechanism for arresting the carriage at variable

positions in the travel thereof, said mechanism including a plurality of fulcrumed members movable variable extents and by the variation in the extent of movement of 5 each of which a variation in the point of arrest of the carriage may be effected, and means for varying the position of the fulcrum of said members relatively to the members to bring about a variation in the extent 10 of movement thereof.

7. In a typewriting machine, the combination of a carriage; and tabulator mechanism for arresting the carriage at variable positions in the travel thereof, said mechanism 15 including a plurality of key controlled fulcrumed members each under control of a separate key and movable variable extents, the variable extent of movement of each of said members bringing about a variation in 20 the point of arrest of the carriage, and key controlled means for varying the position of the fulcrum of said members to change the leverage and thus bring about a variation in the extent of movement of each of said 25 members.

8. In a typewriting machine, the combination of a carriage; and tabulator mechanism for arresting the carriage at variable positions in the travel thereof, said mechanism 30 including a plurality of key controlled fulcrumed members each under control of a separate key and movable variable extents and by the variable extent of movement of each of which members a variation in the 35 points of arrest of the carriage may be effected, key controlled means for varying the position of the fulcrum of said members relatively to the members to change the leverage and thus bring about a variation in 40 the extent of movement of each member, and automatically operating means for locking said fulcrum in any of the variable positions to which it may be moved.

9. In a typewriting machine, the combination of a carriage; and tabulator mechanism for arresting the carriage at variable positions in the travel thereof, said mechanism including a key actuated stop controlling lever having variable extents of movement, the variation in the extent of movement of said lever bringing about a variation in the point of arrest of the carriage, and means for varying the position of the fulcrum of said lever relatively to the lever 55 to change the leverage and thus cause a variation in the movement which may be given said lever.

10. In a typewriting machine, the combination of a carriage; and tabulator mechanism for arresting the carriage at variable positions in the travel thereof, said mechanism including a plurality of variably movable key controlled fulcrumed members each under control of a separate key and by the 65 variable movement of each of which mem-

bers a variation in the point of arrest of the carriage may be effected, key controlled means for varying the position of the fulcrum of said members to bring about a variation in the movement thereof, automatically 70 operating means for locking said fulcrum in any of the variable positions to which it may be moved, and automatically operated means for releasing said locking means at an actuation of one of the keys for 75 controlling said members.

11. In a typewriting machine, the combination of a carriage; and tabulator mechanism for arresting the carriage at variable positions in the travel thereof, said mechanism including a variably movable key actuated stop controlling lever, the variation in the movement of said lever bringing about a variation in the point of arrest of the carriage, means for varying the position of the 80 fulcrum of said lever and thus cause a variation in the movement which may be given said lever, automatically operating means for locking said fulcrum in any of the variable positions to which it may be moved, 85 and automatically operating means for releasing said locking means at an actuation of the lever by its key controlled means.

12. In a typewriting machine, the combination of a carriage, a series of graduated 95 tabulator stops, a series of selecting stops co-operative therewith, key controlled fulcrumed members for effecting variable extents of relative movement between the selecting stops and the graduated stops, and 100 means for varying the position of the fulcrum of said fulcrumed members and thus controlling the variation in the relative movement that may be effected between said selecting stops and said graduated stops. 105

13. In a typewriting machine, the combination of a carriage, a column stop bar carried thereby, a series of graduated column stops carried by said column stop bar and adjustable to different positions along the bar, a co-operative stop, a key controlled fulcrumed member for effecting variable extents of relative movement between said co-operative stop and said graduated column stops to bring them one into the path of the other and to vary the columnar position of arrest of the carriage, and leverage changing means for varying the position of the fulcrum of said fulcrumed member and thereby controlling the variation in the extent of relative movement between the co-operative stop and the column stops. 115

14. In a typewriting machine, the combination of a carriage, a column stop bar carried thereby, a series of graduated column 120 stops carried by said column stop bar and adjustable to different positions along the bar, a co-operative stop, a key controlled fulcrumed member for effecting variable extents of relative movement between said co- 125

operative stop and said graduated column stops to bring them one into the path of the other and to vary the columnar position of arrest of the carriage, leverage changing 5 means for varying the position of the fulcrum of said fulcrumed member and thereby controlling the variation in the extent of relative movement between the coöperative stop and the column stops, and automatically 10 actuated means for locking said fulcrum in any of the variable positions to which it may be moved.

15. In a typewriting machine, the combination of a carriage, a column stop bar carried thereby, a series of graduated column stops carried by said column stop bar and adjustable to different positions along the bar, a coöperative stop, a key controlled fulcrumed member for effecting variable extents of relative movement between said coöperative stop and said graduated column stops for varying the columnar position of arrest of the carriage, means for varying the position of the fulcrum of said fulcrumed member, thereby controlling the variation in the extent of relative movement between the coöperative stop and the column stops, automatically 25 actuated means for locking said fulcrum in any of the variable positions to which it may be moved, and automatically actuated means for releasing said locking means by an actuation of the means for effecting a relative movement between said coöperative stop and the column stops.

30 16. In a typewriting machine, the combination of a carriage, a column stop bar carried thereby, a series of graduated column stops carried by said column stop bar and adjustable to different positions along the bar, a series of coöperative denominational stops, key controlled fulcrumed members for effecting variable extents of relative movement between the denominational stops and the column stops to bring them one into the path of the other, a fulcrum for said fulcrumed members, and leverage changing 35 means for varying the position of said fulcrum relatively to said fulcrumed members and thereby controlling the extent of relative movement effected between said denominational stops and said column stops.

40 17. In a typewriting machine, the combination of a carriage, a column stop bar carried thereby, a series of graduated column stops carried by said column stop bar and adjustable to different positions along the bar, a series of coöperative denominational stops, key controlled fulcrumed members for effecting variable extents of relative movement between the denominational stops and the column stops to bring them one into the path of the other, a fulcrum for said fulcrumed members, leverage changing means 45 for varying the position of said fulcrum relatively to said fulcrumed members and

thereby controlling the extent of relative movement effected between said denominational stops and said column stops, and automatically operating means for locking said fulcrum in any of the variable positions to which it may be moved. 70

18. In a typewriting machine, the combination of a carriage, a column stop bar carried thereby, a series of graduated column stops carried by said column stop bar and adjustable to different positions along the bar, a series of coöperative denominational stops, key controlled fulcrumed members for effecting variable extents of relative movement between the denominational stops and the column stops to bring them one into the path of the other, a fulcrum for said fulcrumed members, means for varying the position of said fulcrum, thereby controlling the extent of relative movement effected between said denominational stops and said column stops, automatically operating means for locking said fulcrum in any of the variable positions to which it may be moved, and automatically operating means for releasing said locking means. 80

19. In a typewriting machine, the combination of a carriage, a column stop bar carried thereby, a series of graduated column stops carried by said column stop bar and adjustable to different positions along the bar, a series of independently movable denominational stops each movable variable extents into the paths of said graduated column stops to determine the columnar position of arrest of the carriage, fulcrumed actuating members for so moving the denominational stops, a separate denominational key for each of said members, a fulcrum for said actuating members, and key actuated means for varying the position of said fulcrum relatively to said actuating members and thereby controlling the variable extents of movement that may be given to each of said denominational stops. 90

20. In a typewriting machine, the combination of a carriage, a column stop bar carried thereby, a series of graduated column stops carried by said column stop bar and adjustable to different positions along the bar, a series of independently movable denominational stops each movable variable extents into the paths of said graduated column stops to determine the columnar position of arrest of the carriage, fulcrumed actuating members for so moving the denominational stops, a separate denominational key for each of said members, a fulcrum for said actuating members, key actuated leverage changing means for varying the position of said fulcrum and thereby controlling the variable extents of movement that may be given to each of said denominational stops, and automatically actuated means for locking said fulcrum in 100 105 110 115 120 125 130

any of the variable positions to which it may be moved.

21. In a typewriting machine, the combination of a carriage, a column stop bar carried thereby, a series of graduated column stops carried by said column stop bar and adjustable to different positions along the bar, a series of independently movable denominational stops each movable variable distances into coöperative relation with said graduated column stops to determine the columnar position of arrest of the carriage, fulcrumed actuating members for so moving the denominational stops, a separate denominational key for each of said members, a fulcrum for said actuating members, key actuated means for varying the position of said fulcrum, thereby controlling the variable extents of movement that may be given to each of said denominational stops, automatically actuated means for locking said fulcrum in any of the variable positions to which it may be moved, and automatically operating means controlled by an actuation of any denominational key for releasing said locking means.

22. In a typewriting machine, the combination of a carriage; and tabulator mechanism for arresting the carriage at variable positions in the travel thereof, said mechanism including a variably movable fulcrumed member, by the variable movement of which the variation in position of arrest of the carriage is determined, means for varying the position of the fulcrum of said member, thereby causing a variation in the movement which may be given said member, said fulcrum varying means comprising a series of key actuated members operating on said fulcrum to move it to different positions, and locking means coöperative with each of said key actuated members to lock it in the operative position and thereby lock the fulcrum in any of the variable positions to which it may be moved by said members.

23. In a typewriting machine, the combination of a carriage; and tabulator mechanism for arresting the carriage at variable positions in the travel thereof, said mechanism including a variably movable fulcrumed member, by the variable movement of which the variation in position of arrest of the carriage is determined, means for varying the position of the fulcrum of said member, thereby causing a variation in the movement which may be given said member, said fulcrum varying means comprising a series of key actuated members operating on said fulcrum to move it to different positions, locking means coöperative with each of said key actuated members to lock it in the operative position and thereby lock the fulcrum in any of the variable positions to which it may be moved by said members,

and automatically operating means actuated at an operation of the tabulating mechanism for releasing said locking means.

24. In a typewriting machine, the combination of a carriage; and tabulator mechanism for arresting the carriage at variable positions in the travel thereof, said mechanism including a variably movable fulcrumed member, by the variable movement of which a variation in position of arrest of the carriage is determined, means for varying the position of the fulcrum of said member, thereby causing a variation in the movement which may be given said member, said fulcrum varying means comprising a movable frame carrying the fulcrum, and a series of key actuated devices operable on said frame to move it different distances.

25. In a typewriting machine, the combination of a carriage; and tabulator mechanism for arresting the carriage at variable positions in the travel thereof, said mechanism including a variably movable fulcrumed member, by the variable movement of which a variation in position of arrest of the carriage is determined, means for varying the position of the fulcrum of said member, thereby causing a variation in the movement which may be given said member, said fulcrum varying means comprising a movable frame carrying the fulcrum, a series of key actuated devices operable on said frame to move it different distances, and automatically operating means for locking said frame in any of the different positions to which it may be moved by said key actuated devices.

26. In a typewriting machine, the combination of a carriage; a column stop bar; column stops carried thereby; a coöperative stop; and means for effecting a relative variable extent of movement between said coöperative stop and said column stop bar, said means comprising a fulcrumed member movable variable extents; and means for varying the position of the fulcrum relatively to said member to vary the extent of movement of the member and to cause a variation in the extent of relative movement between said coöperative stop and the column stops.

27. In a typewriting machine, the combination of a carriage; a column stop bar; column stops carried thereby; a coöperative stop; and means for effecting a relative variable movement between said coöperative stop and said column stop bar, said means comprising a variably movable fulcrumed member, and a series of keys for varying the position of the fulcrum of said member to vary the movement of the member and to cause a variation in the relative movement between said coöperative stop and the column stops, each key controlling a different position of the fulcrum.

28. In a typewriting machine, the combination of a carriage; a column stop bar; column stops carried thereby; denominational stops; and means for effecting a variable relative movement between the denominational stops and said column stop bar toward and away one from the other, said means comprising leverage changing means operable at will to determine the extent of 5 variation in the relative movement between the denominational stops and the column stop bar.
29. In a typewriting machine, the combination of a carriage; a column stop bar; column stop carried thereby; denominational stops; and means for effecting a variable relative movement between the denominational stops and said column stop bar, said means comprising a variably 10 movable fulcrum, and a series of keys having a uniform dip for varying the position of said fulcrum, thereby controlling the variation in the relative movement between the denominational stops and the column stop bar, each key controlling a different position of the fulcrum.
30. In a typewriting machine, the combination of a carriage; tabulator stops whose contact faces are arranged in different 15 paths; a coöperative stop; means for effecting a relative variable movement between said coöperative stop and the contact faces of said tabulator stops, so as to bring the coöperative stop and any desired tabulator stop into coöperative relation, said means comprising leverage changing means operable at will to determine which tabulator stop the coöperative stop will be brought into coöperation with.
31. In a typewriting machine, the combination of a carriage; column stops whose contact faces are arranged in different paths; a coöperative stop; means for effecting a relative variable movement between 20 said coöperative stop and the contact faces of said column stops so as to bring the coöperative stop and any desired column stop into coöperative relation, said means comprising a variably movable fulcrumed member, and a series of independently operable keys having a uniform dip for varying the position of the fulcrum of said fulcrumed member to vary the movement given to 25 said member and the part controlled thereby, each key controlling a different position of the fulcrum.
32. In a typewriting machine, the combination of a carriage; tabulating mechanism comprising an auxiliary key, and a normally inoperative device controlled by a part of the tabulating mechanism for releasing the carriage; and means for bringing said carriage releasing device and the part of the tabulating mechanism with 30 which it co-acts into coöperative relation 65 when said auxiliary key is actuated.
33. In a typewriting machine, the combination of a carriage; and tabulating mechanism comprising key actuated column selecting means, a normally inoperative carriage releasing device, and means whereby said carriage releasing device is moved to operative position when the key actuated column selecting means are actuated.
34. In a typewriting machine, the combination of a carriage; and tabulating mechanism comprising key actuated column selecting means, key actuated denominational selecting means, a normally inoperative carriage releasing device, and means whereby 70 said carriage releasing device is moved to operative position to be actuated by the denominational selecting means, when the key actuated column selecting means are actuated.
35. In a typewriting machine, the combination of a carriage, tabulating mechanism comprising key-controlled tabulator-stop actuating devices, a normally inoperative carriage releasing device, a key separate from 75 the keys which control the tabulator-stop actuating devices, and means controlled by said separate key for moving said carriage releasing device into the paths of said key controlled actuating devices to be actuated 80 thereby.
36. In a typewriting machine, the combination of a carriage, coöperative tabulator stops, and leverage changing means operable at will to cause a variation in the movement 85 of certain of said stops relatively to others to vary the point of arrest of the carriage.
37. In a typewriting machine, the combination of a carriage, coöperative tabulator stops, key controlled means for effecting a 90 relative movement between said stops to bring them into coöperative relation, and leverage changing means under separate key control and operable at will to cause a variation in the extent of movement of certain 95 of said stops relatively to others when actuated by the first mentioned key controlled means, a variation in the leverage changing means causing a variation in the point of arrest of the carriage.
38. In a typewriting machine, the combination of a carriage, graduated tabulator stops, a coöperative stop, key controlled means for effecting a relative variable movement between said coöperative stop and said 100 graduated stop to vary the position of arrest of the carriage, and leverage changing means under separate key control and operable at will for varying the relative movement of the stops effected under control of 105 said first mentioned key controlled means.
39. In a typewriting machine, the combination of a carriage; and key tabulator 110

mechanism for arresting the carriage at various positions in its travel, said mechanism including leverage changing means operable at will to determine the position of 5 arrest of the carriage.

40. In a typewriting machine, the combination of a carriage, a series of column stops with the contact portions thereof in different paths, a series of denominational stops 10 each variably movable to bring it into co-operative relation with the contact portions of different column stops to vary the columnar position of arrest of the carriage, and leverage changing means operable at will to 15 control said variable movement of the denominational stops.

41. In a typewriting machine, the combination of a carriage; and tabulator mechanism including a variably movable stop, the 20 variation in the movement of said stop varying the position of arrest of the carriage, and leverage changing mechanism movable independently of the stop but operative to determine the variation in the movement of 25 the stop.

42. In a typewriting machine, the combination of a carriage; and tabulating mech-

anism including a variably movable fulcrumed member, the variation in the movement of said member varying the position 30 of arrest of the carriage, and means operable at will to vary the position of the fulcrum of said fulcrumed member independently of the member.

43. In a typewriting machine, the combination of a carriage; and key tabulator mechanism for arresting the carriage at various positions in its travel, said mechanism including leverage changing means operable at will to determine the position of 35 arrest of the carriage, means for locking the leverage changing means in the various positions to which it may be shifted, and automatically operating means for releasing said locking means.

Signed in the borough of Manhattan, city of New York, in the county of New York, and State of New York, this 4th day of December A. D. 1911.

JOHN WALDHEIM.
